INVENTOR.

Sahatel G. Mandalian

BY Horatio E. Bellows

ATTORNEY

UNITED STATES PATENT OFFICE.

SAHATIEL G. MANDALIAN, OF NORTH ATTLEBORO, MASSACHUSETTS.

LAMP SHADE.

Application filed December 16, 1921. Serial No. 522,743.

To all whom it may concern:

Be it known that I, SAHATIEL G. MANDALIAN, a citizen of the United States, residing at North Attleboro, in the county of 5 Bristol and State of Massachusetts, have invented certain new and useful Improvements in Lamp Shades, of which the following is a specification.

My invention relates to lamp shades and 10 has for its essential objects security of engagement with the lamp and facile application thereto and removal therefrom protection of the lamp from accidental fracture, and by a flexible means that allows a degree 15 of visibility therethrough of light and color; and finally grace and beauty of appearance.

To the above ends essentially my invention consists in such parts and in such combinations of parts as fall within the scope 20 of the appended claims.

In the accompanying drawings which form a part of this specification,

Figure 1 is a side elevation of a shade which embodies my invention,

25 Figure 2, a central vertical section thereof, showing a portion of the lamp to which it is attached, broken away,

Figure 3, a perspective section of the frame,

30 Figures 4 and 5, an enlarged fragmentary side elevation and a section respectively of the frame and one form of mesh mantle construction,

Figures 6, 7 and 8, side elevations of other 35 forms of mesh mantle construction,

Figures 9 and 10, a sectional and plan view respectively of a hood, and

Figures 11 and 12, similar views respectively of another form of hood.

40 Like reference characters indicate like parts throughout the views.

The frame of my shade comprises a broad endless plate or ring 12, in this case cylindrical, but which may be polygonal or of 45 other contour. This is provided upon its lower margin with an annular series of perforations 13. Inwardly and downwardly curved arms 14 are fast to the inner face of the ring and are connected by an annular 50 brace 15. Fast in the lower ends of the arms are resilient downwardly and inwardly inclined clamping loops 16. The described frame may be applied to an electric bulb 17 by pressure from above so that the loops 16 55 yields outwardly until the brace 15 rests upon the bulb, whereupon the loops contract

and embrace the same so snugly that the shade cannot accidentally tilt.

A depending flexible metallic mantle or 60 shield 19 is mounted on the ring portion 12 of the frame of such a character as to resist powerful accidental blows that might otherwise destroy the bulb. This shield or mantle comprises a fabric having interstices 20 that permit rays of light therethrough without destroying the protective function of the mantle. At the same time the mantle is of a flexible character to permit vertical folds for artistic effects. All these qualities are 65 present in various metallic mesh fabrics such as scale mesh, ring mesh, lock or unbreakable mesh, and woven mesh.

In Figures 4 and 5 is shown a metallic 70 scale mesh fabric. This mesh is formed by parallel rows of rings 22, each four adjacent rings being united by a flat link or plate 24 with four corner prongs 25 embracing the rings or circular links.

The metallic fabric of ring mesh is shown 75 in Figure 6 composed of parallel rows of ring links 27, each group of four rings being engaged by a ring 28.

In Figure 7 is shown a lock link or unbreakable metallic mesh fabric. Herein the 80 links are arranged in rows and each U shaped folded link 29 has terminal loops 30 through which pass links of an adjacent row.

In Figure 8 is shown one form of woven 85 metallic mesh fabric wherein rows of horizontal wires 31 are basket woven with vertical wires 32. The woven wire mesh fabric, however, is inferior for my purposes to the two forms of link mesh fabric shown in Figures 4 and 6.

A row of suspension rings 33 in the upper margin of the mantle 19 pass through the perforations 13 of the frame. Also suspended from the ring 12 in this instance is an inner textile mantle 35 preferably of an ornamental color or shade, and preferably of a thin silk texture. A gathering thread 37 around its upper margin is threaded through the suspension rings 33. To maintain the same in symmetrical position it is weighted by a metal ring 39 in its 90 bottom portion retained by folding the lower edge of the fabric over the ring and attaching the edge by a row of stitching 40, thus forming an integral sleeve 41.

In some instances my shade is provided 110 with a hood, cover, or shield to intercept the vertical rays. One form of hood is

shown in Figures 8 and 9 wherein an arched circular plate 43 provided with interstices 44 has fast to its center a handle or knob 45. A peripheral lateral flange portion 47 is adapted to overlap the ring 12 while an inset integral depending annular flange 49 abuts against the inner face of the ring. A thin textile lining strip 50 of a color corresponding with the member 35 has its peripheral edge 50 frictionally clamped against the flange 49 by a snugly fitting metallic band 51.

Another form of hood, shown in Figures 10 and 11, comprises an arched plate 53 provided with interstices 54. Integral with the periphery of the plate are three depending legs 56 having outwardly directed feet 58 provided with slots 59. The feet or fingers 58 rest on the member 15 while the

fingers formed by the slots 59 embrace the 20 arms 14.

I claim:

A lamp shade comprising an annular plate having perforations in its lower margin, inwardly and downwardly inclined 25 arms fast to said plate above the perforations, an annular brace connecting said arms, resilient loops on said arms below said brace and inclined downwardly and inwardly to embrace an electric bulb, and a 30 depending flexible metallic shield suspended from said plate and movably supported from the perforated lower margin of the same.

In testimony whereof I have affixed my 35 signature.

SAHATIEL G. MANDALIAN.
